CLAIM

The ornamental design for an ink bottle for printer, as shown and described.

DESCRIPTION

1.1 is a front view of an embodiment of the ink bottle for printer showing the new design;

1.2 is a rear view thereof;

1.3 is a top plan view thereof;

1.4 is a bottom plan view thereof;

1.5 is a left side view thereof;

1.6 is a right side view thereof;

1.7 is a top perspective view thereof;

1.8 is a bottom perspective view thereof;

2.1 is a front view of another embodiment of the ink bottle for printer;

2.2 is a rear view thereof;

2.3 is a top plan view thereof;

2.4 is a bottom plan view thereof;

2.5 is a left side view thereof;

2.6 is a right side view thereof;

(Continued)

2.7 is a top perspective view thereof;
2.8 is a bottom perspective view thereof.

1 Claim, 16 Drawing Sheets
